JAMES A. CLEMENTS, OF ABINGDON, ILLINOIS.

AUTOMATIC GATE-CATCH.

1,177,487.

Specification of Letters Patent. Patented Mar. 28, 1916.

Application filed July 26, 1913. Serial No. 781,400.

To all whom it may concern:

Be it known that I, JAMES A. CLEMENTS, a citizen of the United States, residing at Abingdon, in the county of Knox and State 5 of Illinois, have invented a new and useful Automatic Gate-Catch, of which the following is a specification.

The invention relates to a combined automatic gate catch and gate support.

10 The object of the present invention is to improve the construction of automatic gate catches, and to provide a simple, inexpensive and efficient automatic double acting gravity gate catch and gate support of strong and 15 durable construction, designed for use on farm gates opening in either direction and adapted to support a gate in its closed position and effectually prevent the gate from sagging or pulling the hinge post over or 20 from being lifted out of engagement with the engaging means by smart stock.

The invention also has for its object to provide an automatic catch of this character adapted to be easily operated by a pedestrian 25 or by an equestrian without dismounting, and equipped with means for excluding rain, snow and sleet from its interior so that the same will not interfere with the proper operation of the automatic catch.

30 With these and other objects in view, the invention consists in the construction and novel combination of parts hereinafter fully described, illustrated in the accompanying drawing, and pointed out in the claims here- 35 to appended; it being understood that various changes in the form, proportion, size and minor details of construction, within the scope of the claims, may be resorted to without departing from the spirit or sacrific- 40 ing any of the advantages of the invention.

In the drawing:—Figure 1 is a front elevation of an automatic catch and gate support, constructed in accordance with this invention, the latch, which is carried by the 45 gate, being in section. Fig. 2 is a vertical sectional view of the same, taken transversely with relation to the gate. Fig. 3 is a side elevation of the automatic gate catch and gate support. Fig. 4 is a vertical sec- 50 tional view on the line 4—4 of Fig. 1, the latch member, which is carried by the headend of the gate, being removed. Fig. 5 is a horizontal sectional view on the line 5—5 of Fig. 1. Fig. 6 is a detail view of the re- movable front of the housing. Fig. 7 is a 55 detail view of the adjustable latch member, which is carried by the gate.

Like numerals of reference designate corresponding parts in all the figures of the drawing. 60

In the accompanying drawing in which is illustrated the preferred embodiment of the invention, the automatic gate catch comprises in its preferred construction an upper housing 1 and a lower supporting flange or ledge 2, located below the housing in spaced relation with the same to form a guideway 3 for the passage of a latch member 4. The supporting ledge or flange 2, which consists of a central horizontal portion and oppositely inclined side portions, extends inwardly or rearwardly beyond the vertical plane of the rear wall of the housing, and it is connected with the latter by a vertical back plate 5 and a horizontal web or flange 6, extending rearwardly from the back of the housing at the bottom thereof. The housing, which is approximately rectangular, is composed of a top wall, a vertical rear wall, vertical side or end walls and a removable front wall or plate 7, secured to the body portion of the housing by an upper horizontal bolt 8, extending through aligned openings in the front and rear walls of the casing and through or into a post 9 so that it fastens the front plate of the housing to the body thereof and also assists in firmly securing the housing to the post, as shown. The back plate 5 is preferably provided at its lower portion with a centrally arranged vertical slot 10, extending upwardly from the lower edge of the said back plate 5 and receiving a lower bolt 11, which also pierces the said post. The housing is provided with an integral centrally arranged bottom portion 12, extending forwardly from the back plate and arranged in spaced relation with the end walls to form bottom openings 13, which guide lower engaging heads 14 of a pair of vertically movable locking dogs or 95 catches 15. The housing is also provided in its top wall with guide openings 16, which are formed by slots extending inwardly from the front edges of the top wall of the housing; and the said dogs or catches are retained in the upper guide openings by spaced lugs 17, projecting into the front portions 100 of the top guide openings 16. The remov-

able front plate is provided at its ends with notches 18 to engage with forwardly projecting lugs 19 of the end walls of the housing, and it has upper and lower inwardly 5 extending lugs 20, which fit against the inner or lower face of the top wall of the housing and the upper face of the bottom portion 12 of the same. The housing is provided at its ends with laterally projecting bracing 10 flanges 21, which are located at the ends of the guideway 3, and the rear plate 5 is provided with vertical ribs or flanges 22, which are embedded in the post, as clearly illustrated in Fig. 3 of the drawing.

15 The vertically movable dogs or catches, which are in the form of gravity acting plungers, have their intermediate portions reduced to fit the upper guide openings 16, and they are enlarged at the upper ends of 20 the intermediate portions to form caps or 25 closures 23, which extend beyond the upper guide openings and fit against the top of the housing for excluding snow and ice from the interior of the same. The lower engaging heads of the dogs or catches 15 are tapered to provide outer inclined side faces 24, and they have vertical inner faces 25, arranged in spaced relation and adapted to receive between them the latch member 4.

30 The lower engaging heads are of a size to fill the bottom guide openings of the housing, and they are limited in their downward movement by the enlarged cap portions 23, and their upward movement is limited by 35 upper shoulders formed by the engaging heads 14. The dogs or catches, which are interchangeable and independently operable, are adapted to be lifted automatically by the latch member, and they automatically 40 drop into engagement with the same and confine the said latch member on the central portion of the supporting flange or ledge, which effectually prevents the gate from sagging and from straining and pulling over 45 the hinge post. The upper ends of the dogs or catches are provided with eyes or openings 26 through which passes a double lever 27, constructed of No. 10 wire or other suitable material having horizontal terminal 50 portions and an intermediate loop 28, located between the dogs or catches and adapted to retain the lever in the said eyes or openings 26. The upper and lower walls of the eyes or openings are rounded, as clearly shown 55 in Fig. 2 of the drawing, and the terminal portions of the double lever project beyond the dogs or catches and are adapted to be either raised or depressed for lifting the said dogs or catches. The double acting 60 lever is adapted to fulcrum on either one of the independently movable locking dogs or catches 15, and when one end of the lever is lifted it raises the dog or catch at that side of the catch, and by bearing down on 65 one end of the lever, the dog or catch at

the other side of the catch is raised so that the operator has complete control of the catch at either side. The latch member slides freely up the inclines of the ledge or flange and readily passes under either dog or catch, but when it passes either dog or catch it is caught and securely confined until released by the lifting of one of the dogs or catches.

70 The latch member 4 consists of a front or outer engaging portion and a shank 28^a. The outer engaging portion consists of an upper central rib or flange 29 and a lower transversely tapered portion 30, projecting laterally beyond the side faces of the upper 75 rib or flange and presenting inclined side faces adapted to ride readily up the inclined 80 terminal portions of the ledge or flange 2. The upper rib or flange is adapted to engage the inclined outer edges or faces of the heads 85 14 of the catches or dogs for automatically lifting the latter when the gate is swung to its closed position. The central upper rib or flange has straight side faces, and when it is arranged between the spaced inner 90 vertical engaging edge of the catches or dogs, it is securely retained in the space between the dogs or catches and is effectually prevented from being released by stock. The shank 28^a consists of a vertical 95 plate provided with upper and lower horizontal slots 31 provided at intervals with circular enlargements 32, adapted to receive bolts for adjustably securing the latch member to the front bar 33 of a gate. The slots 100 and the bolts enable the latch member to be adjusted inwardly and outwardly to engage properly the dogs or catches of the latch.

95 What is claimed is:—

1. A gate catch including a latch member 105 designed to be mounted on a gate, a housing provided in its top and bottom with guide openings, vertically slidable dogs or catches consisting of lower engaging heads guided in the bottom openings of the housing, reduced intermediate portions extending through and guided in the openings in the top of the housing, an enlarged upper portion located above the casing exteriorly of the same and arranged to rest upon the top 110 of the housing and covering the upper guide openings, and an exterior operating lever mounted on the enlarged upper portions of the dogs, each of which forms a fulcrum for the lever to permit the same to lift the other 115 dog.

2. A gate catch including a latch member 120 designed to be mounted on a gate, a housing, spaced dogs or catches slidable upwardly and downwardly in the housing and extending above the same and provided in their upper ends with eyes, said dogs or catches having lower portions arranged to engage the latch member, and an operating lever 125 arranged exteriorly of the casing and con- 130

sisting of approximately horizontal terminal portions extending through the eyes of the dogs or catches, and an intermediate loop located between the dogs or catches.

5 3. A gate catch including a latch member designed to be mounted on a gate, a housing composed of a body portion provided with upper guide openings formed by slots extending inwardly from one edge, 10 said body portion being also provided with a central body portion spaced from the side walls and forming bottom guide openings, and a front plate having lugs extending in the front portions of the said slots, said 15 front plate having upper and lower lugs fitting between the top wall of the body and the bottom portion thereof, and vertically movable catches slidable in the guide openings and having lower portions for engaging 20 with the latch member.

4. A gate catch including an upper housing, a lower flange or ledge arranged in spaced relation with the housing, dogs or catches depending from the housing and 25 projecting into the space between the same and the said flange or ledge, and a latch member designed to be adjustably mounted on a gate and having a projecting engaging portion arranged to rest upon the flange or 30 ledge and consisting of an upper centrally arranged rib or flange adapted to engage the said dogs or catches, and a lower transversely tapered portion projecting beyond

the said rib or flange and presenting inclined side faces.

5. A gate catch comprising a housing, dogs vertically movable in the housing, and a coacting latch member adjustably mounted on a gate and adapted to be adjusted to coact with the said dogs, said latch member consisting of an outer engaging portion and a shank, said shank being formed of a vertical plate provided with upper and lower horizontal slots provided at intervals with enlargements, and bolts passing through the slots for attaching the shank to the gate.

6. A gate catch including a lower supporting ledge, spaced vertically movable dogs or catches located above the ledge, and a latch member designed to be adjustably mounted on a gate and having a projecting portion arranged to rest upon the ledge, said engaging portion consisting of an upper centrally arranged rib or flange adapted to be engaged by the said dogs or catches, and a lower transversely tapered portion projecting beyond the said rib and presenting inclined side faces.

In testimony, that I claim the foregoing as my own, I have hereto affixed my signature in the presence of two witnesses.

JAMES A. CLEMENTS.
